JONATHAN MOORE, JR., OF BROOKLYN, NEW YORK.

Design No. 4,846, dated April 25, 1871.

DESIGN FOR A CLOCK-FRONT.

The Schedule referred to in these Letters Patent and making part of the same.

To all whom it may concern:

Be it known that I, JONATHAN MOORE, Jr., of Brooklyn, in the county of Kings and State of New York, have invented and produced a new and original Design for Clock-Fronts.

It is adapted to be cast in iron or bronze, or may be molded in papier-maché or other suitable material.

The nature of the design is very fully set forth in the accompanying illustrations which form a part of this specification.

Referring to the drawings—

A is the clock-face, and

B the base.

C and D are figures of two boys in easy reclining attitudes, disposed one on each side of the clock-base, so as to make a symmetrical design. Both are very slightly draped, and one, the left, is reclining on a coarse net, such that the meshes appear very distinctly, while the other, the right, is reclining on a fabric or flowing material having meshes or texture so fine that it appears continuous.

I distinguish the design from others of my own and other manufacture by the title "Fisher-boys." The base below and the top and sides of the clock-face above are ornamented by suitable architectural and ornamental devices.

I claim—

The design for a clock-front, as herein set forth and described.

In testimony whereof I have hereunto set my name in presence of two subscribing witnesses.

JONATHAN MOORE, JR.
